To all whom it may concern:

Be it known that I, Charles I. Rockmore, a citizen of the United States, residing at 201 Eastern Parkway, Brooklyn, in the county of Kings and State of New York, have invented a new, original, and ornamental Design for a Shoe or Similar Article, of which the following is a specification, reference being had to the accompanying drawing, forming part thereof.

In the drawing—

Fig. 1 is a side elevation of a shoe, slightly in perspective, showing my new design. The two sides of said shoe are identical in appearance.

Fig. 2 is a rear elevation.

The characteristic feature of the invention is the surface appearance of the upper. Said upper is formed with irregular plaiting of the design and configuration shown in the drawing. The shape of the upper may be varied without departing from the invention, which consists essentially in the aforesaid surface appearance of the upper.

I claim:

The ornamental design for a shoe or similar article, substantially as shown and described.
